(57) **CLAIM**

The ornamental design for a rock claw for demolition hammer, as shown and described.

DESCRIPTION

FIG. 1 is a pictorial view of a rock claw for demolition hammer showing our new design. The broken line showing of an additional rock claw and housing is shown for environmental purposes only and forms no part of the claimed design. FIG. 2 is a front elevational view of a rock claw of FIG. 1. FIG. 3 is a bottom plan view of the rock claw of FIG. 2. FIG. 4 is a right side elevational view thereof, the left side view being a mirror image thereof. FIG. 5 is a back elevational view of the rock claw of FIG. 2. FIG. 6 is a top plan view of the rock claw of FIG. 2. FIG. 7 is a pictorial view of the rock claw of FIG. 2; and, FIG. 8 is another pictorial view of the rock claw of FIG. 2.
